SLURRY PUMP

Bobbie R. Smith, 737 SW. 50th St.,
Oklahoma City, Okla. 73109
Filed Sept. 22, 1965, Ser. No. 489,120
14 Claims. (Cl. 103—49)

This invention relates generally to improved reciprocating pumps useful for pumping concrete slurry and the like. More particularly, but not by way of limitation, this invention relates to an improved slurry pump having an improved valve therein.

In one aspect, this invention contemplates an improved pump valve comprising: a housing having an open end, a closed end, and first, second and third openings extending through the wall thereof; a valve member pivotally mounted in the housing and having a bore forming an open end and a closed end, the closed end being disposed adjacent the closed end of the housing, the valve member also including first and second spaced, annular flanges encircling the valve member in sealing engagement with the housing, a pair of spaced members extending between and connected with the flanges, and an aperture extending through the valve member between the flanges and spaced members; means journaling the valve member in the housing; and, means connected with the open end of the valve member for pivoting the valve member from a position aligning the aperture with the first opening to a position aligning the aperture with the second opening.

In another aspect, this invention contemplates an improved pump for pumping concrete slurry or the like comprising: the pump valve set forth hereinbefore; first and second cylinders having an open end connected with the first and second openings, respectively, in the valve housing; a piston in each of the cylinders; driving means operably connected with the pistons for alternately reciprocating the pistons; a hopper mounted on the open end of the valve member and having an opening in communication with the bore in the valve member; and, means connected with the open end of the valve member and operably interconnected with the driving means for pivoting the valve member from a position wherein the aperture is aligned with the first opening when the piston in the first cylinder is moving relatively away from the open end thereof to a position wherein the aperture is aligned with the second opening when the piston in the second cylinder is moving relatively away from the open end thereof.

One object of this invention is to provide an improved pump capable of handling a slurry containing relatively large solid materials, such as the aggregate used when mixing concrete.

Another object of this invention is to provide an improved valve for use in a pump capable of handling concrete slurry and the like.

Still another object of the invention is to provide an improved concrete pump having an extended service life.

One further object of the invention is to provide an improved concrete pump and improved valve for use therein that can be quickly, easily and economically manufactured.

The foregoing and additional objects and advantages of the invention will become more apparent as the following detailed description is read in conjunction with the accompanying drawings wherein like reference characters denote like parts in all views and wherein:

FIG. 1 is a side elevation view of a pump and valve constructed in accordance with the invention, a portion of the apparatus having been removed for clarity of illustration;

FIG. 2 is a horizontal cross-sectional view of the pump

2

and valve of FIG. 1, taken substantially along the line 2—2 of FIG. 1;

FIG. 3 is an enlarged, vertical cross-sectional view of the valve illustrated in FIG. 1, taken substantially along the line 3—3 of FIG. 1;

FIG. 4 is a schematic diagram illustrating the operation and control of the pump and valve of FIG. 1; and,

FIG. 5 is a cross-sectional view similar to FIG. 3, but illustrating another embodiment of valve also constructed in accordance with the invention.

Embodiment of FIG. 1

Referring to the drawing and to FIG. 1 in particular, shown therein and generally designated by the reference character 10 is a slurry pump constructed in accordance with the invention. The slurry pump 10 includes a pair of cylinders 12 and 14 (see FIG. 2) connected to a pump valve that is generally designated by the reference character 16.

As shown in FIG. 1, the slurry pump 10 also includes a hemispherically shaped hopper 18 that is attached to the pump valve 16 by a plurality of brackets 20. The hopper 18 has a discharge opening 19 (see FIG. 3) in the lower portion thereof adjacent the pump valve 16. A pair of valve operating cylinders 22 and 24 (see FIG. 4) are operably connected to the pump valve 16 as will be described more fully hereinafter. The cylinders 22 and 24 are connected to a frame 26 that is also connected with the pump valve 16 for the purpose of supporting the pump valve 16 on the vehicle or skid upon which the pump 10 is mounted. The vehicle or skid upon which the pump 10 is to be mounted is not shown, it being believed that the method and apparatus used for mounting the pump 10 will be readily apparent to those skilled in the art. Also, only a portion of the frame 26 is illustrated, the remaining portion having been removed to more clearly illustrate the structure of the pump 10.

FIGS. 2 and 3 illustrate more clearly the structure of the pump valve 16. As shown therein, the pump valve 40 16 includes a hollow cylindrical housing 28 having an open upper end 30 and a closed lower end 32. The housing 28 has an opening 33 extending through the side wall thereof. The opening 33 is in fluid communication with the cylinder 19 through an adapter 34 that is connected with the cylinder 14. A second opening 36 also extends through the side wall of the housing 28 providing communication with the cylinder 12 through an adapter 38 that is connected with the cylinder 12 and with the housing 28. A third opening 40 extends through the side wall of the housing 28 having a discharge member 42 connected therewith. As shown in FIG. 1, a flexible conduit 44 is connected with the end of the discharge member 42 for the purpose of delivering the slurry from the pump 10 to the location wherein the slurry is to be used.

As shown most clearly in FIG. 3, an O-ring seal 46 is located in an annular groove 48 in the interior of the housing 28. Similarly, a second O-ring seal 50 is located in an annular groove 52 also located within the interior 60 of the housing 28 in spaced parallel relation with the annular groove 48.

A hollow valve member 54 is pivotally disposed within the interior of the housing 28. As clearly illustrated in FIG. 3, the hollow valve member 54 has a closed lower end 56 that extends radially outwardly forming a lower flange 58 thereon. The outer periphery of the lower flange 58 is in sealing engagement with the O-ring seal 50 in the valve housing 28.

A shaft 60 extends downwardly from the closed lower end 56 of the valve member 54 through the closed lower end 32 of the valve housing 28. A thrust bearing 62, encircling the shaft 60, is operably disposed between the

closed lower end 56 of the valve member 54 and the closed lower end 32 of the valve housing 28 to journal the valve member 54 in the housing 28. The thrust bearing 62 is of conventional construction and supports the valve member 54 both against thrust loads and radial loads that may be imposed thereon.

The valve member 54 includes a second exterior flange 64 extending radially outwardly therefrom and having its outer periphery in sealing engagement with the O-ring seal 46 in the valve housing 28. As can be appreciated from viewing FIG. 3, the arrangement of the lower flange 58 and the flange 64 in combination with the O-ring seals 46 and 50 forms an annular chamber 66 between the valve housing 28 and the valve member 54.

As shown in FIG. 2, a pair of spaced, vertically extending members 68 and 70 (shown in dash lines in FIG. 3) extend between the flanges 58 and 64. Each of the members 68 and 70 has one edge attached to the valve member 54 and has the other edge thereof in engagement with the interior of the valve housing 28. The valve member 54 also includes an aperture 72 that extends through the wall thereof providing communication from the interior of the hollow valve member 54 into the space defined by the flanges 58 and 64 and the vertically extending members 68 and 70 for purposes that will become more apparent as the description proceeds.

An upper annular flange 74 encircles the upper open end 76 of the valve member 54. The upper annular flange 74 is connected to a sleeve 78 that is attached to the valve member 54 by a plurality of threaded fasteners 80. A shorter sleeve 82 is connected with and depends from the upper annular flange 74 near the outer periphery thereof.

The sleeve 82 carries a bearing member 84 that may be suitably constructed from a lubricant impregnated sintered bronze or the like. The bearing member 84 is in engagement with the valve housing 28 to journal the upper end of the valve member 54 therein.

A partially threaded aperture 86 extends through the valve housing 28 adjacent the exterior of the bearing member 84. A zirk fitting 88 is threaded into the partially threaded aperture 86 to provide for lubrication of the bearing member 84 from the exterior of the pump valve 16.

A pair of operating members 90 and 92 are connected with the upper annular flange 74 by a plurality of threaded fasteners 94. As shown in FIGS. 1 and 4, the operating members 90 and 92 (only the member 90 is shown in FIG. 1) are pivotally connected with rod portions 95 and 96, respectively, of pistons 98 and 100 that are reciprocally disposed in the cylinders 22 and 24, respectively.

Referring to FIGS. 2 and 4, it can be seen that the cylinders 12 and 14 have pistons 102 and 104 reciprocally disposed therein. A piston rod 106 of the piston 102 is connected with a piston 108 disposed in a hydraulic cylinder 110 (see FIG. 4). Similarly and as is also shown in FIG. 4, the piston 104 disposed in the cylinder 14 has a piston rod 112 connected with a piston 114 that is reciprocally disposed in a hydraulic cylinder 116.

Referring to FIG. 4, the pump 10 is shown schematically to illustrate the arrangement of the hydraulic apparatus for both actuating the pump pistons 102 and 104 and for operating the pump valve 16. As shown therein, the hydraulic cylinders 110 and 116 are connected with a solenoid-actuated, four-way valve 118 by conduits 120 and 122, respectively. The solenoid-actuated valve 118 is also connected with a pump 124 by a conduit 126 and with a hydraulic fluid reservoir 128 by a conduit 130.

The solenoid-actuated valve 118 is a commercially available valve arranged to permit flow therethrough in the direction of the solid arrows, as shown in FIG. 4, when in one position and, when shifted to another position, to permit flow therethrough in the direction of the dash arrows shown in FIG. 4. Solenoids 119 and 121

are mounted on the valve 118 to shift the valve between the operating positions described.

As illustrated in FIG. 4, the solenoid 119 is connected by a conductor 132 with a ground 133 and by a conductor 134 with a switch 135 that is mounted on the pump 10 in a position to be actuated by the valve operating member 90. A conductor 138 is connected with a battery or source of electrical potential 140. The battery 140 is connected with the ground 133 to complete the electrical circuit associated with the switch 135 and solenoid 119.

The solenoid 121 on the valve 118 is connected with ground 133 by a conductor 139 and with a switch 141 by a conductor 143. The switch 141 is arranged for actuation by the valve operating member 92. A conductor 145 connects the switch 141 with the battery 140.

To complete the hydraulic circuit associated with the cylinders 110 and 116 and the valve 118, a conduit 142 extends between the cylinders 110 and 116 to provide communication therebetween on one side of the pistons 108 and 114. The pump 124 is connected with a suction conduit 144 that extends into the fluid reservoir 128.

A solenoid-actuated, four-way valve 146 is connected with the hydraulic cylinders 22 and 24 by conduits 148 and 150, respectively. The solenoid-actuated valve 146 is a commercially available valve arranged to permit flow therethrough, when in one position, in the direction as shown by the solid arrows in FIG. 4 and, when shifted to another position, to permit flow therethrough in the direction of the dash arrows shown in FIG. 4. Solenoids 147 and 149 are mounted on the valve 146 to shift the valve 146 between the operating positions described.

A conduit 152 connects the solenoid-actuated valve 146 with the conduit 130 that extends from the solenoid-actuated valve 118 to the fluid reservoir 128. A conduit 154 connects the solenoid-actuated valve 146 with the pump 124. Opposite ends of the cylinders 22 and 24 are connected in fluid communication by a conduit 156. Similarly, the other ends of the cylinders 22 and 24 are connected by a conduit 158.

The solenoid 147 is connected with the ground 133 by a conductor 160 and is connected with a switch 162 by a conductor 164. The switch 162 is positioned adjacent the piston rod 106 so that it will be actuated by a switch actuating member 163 mounted on the rod 106. A conductor 166 extends from the switch 162 to the source of electrical potential 140 to complete the electrical circuit associated with the solenoid 147.

The solenoid 149 on the valve 146 is connected with the ground 133 by a conductor 168 and with a switch 170 by a conductor 172. The switch 170 is disposed adjacent the piston rod 112 so that it is actuated by a switch actuating member 174 mounted on the piston rod 112. A conductor 176 connects the switch 170 with the battery 140.

Operation

The operation of the slurry pump 10 may be best understood by reference to FIG. 4. As shown therein, the pump valve 16 has been broken down into two components. The view in the lower left hand portion of FIG. 4 illustrates the pump valve 16 with the upper portion thereof removed similar to the sectional view of FIG. 2. In the lower right hand portion of FIG. 4, the upper annular flange 74 of the valve is illustrated so that the operation of the hydraulic cylinders 22 and 24 to position the valve member 54 may be more clearly illustrated. It will be understood that the pump valve 16 in actual practice is constructed as previously described.

Assuming that the solenoid-actuated valve 118 has been positioned so that the flow therethrough is in the direction of the dash arrows, it can be seen that hydraulic fluid flows from the pump 124 through the conduit 126, through the valve 118 and conduit 122 into the hydraulic cylinder 116. Upon entering the hydraulic cylinder 116, the fluid drives the piston 114 relatively toward the pump valve 16 to the position illustrated in FIG. 4.

As the piston 114 moves relatively toward the pump valve 16, the piston 104 in the cylinder 14 forces any slurry that may be in the cylinder 14 through the adapter 34 and the opening 33 into the annular space 66 formed in the pump valve 16. The slurry is then discharged from the pump valve 16 through the opening 40 into the discharge member 42.

Simultaneously, fluid from the hydraulic cylinder 116 on the opposite side of the piston 114 passes through the conduit 142 into the hydraulic cylinder 110, driving the piston 108 relatively toward the solenoid-actuated valve 118, that is, toward the position illustrated in FIG. 4. The simultaneous movement of the piston 102 in response to the movement of the piston 108 relatively away from the pump valve 16 creates a reduced pressure in the cylinder 12 and adapter 38 so that slurry contained in the hopper 18 (see FIG. 3) flows through the discharge opening 19 therein into the interior of the valve member 54, through the aperture 72, through the adapter 38 and into the cylinder 12.

The valve member 54 is illustrated in FIG. 4 as being positioned with the aperture 72 therein disposed in communication with the cylinder 12. The positioning of the valve member 54 is accomplished by positioning the solenoid-actuated valve 146 so that fluid flow therethrough follows the dash arrows shown in FIG. 4. With the solenoid-actuated valve 146 in this position, fluid flows from the pump 124 through the conduit 154 into the solenoid-actuated valve 146 and through the conduit 148 into the cylinder 22. As the fluid enters the cylinder 22, the piston 98 is driven relatively toward the pump valve 16 and, due to the connection between the piston rod 95 and the valve operating member 90, rotates the upper annular flange 74 and the attached valve member 54 to the position wherein the aperture 72 is in communication with the cylinder 12.

Simultaneously, the fluid in the cylinder 22 on the opposite side of the piston 98 passes through the conduit 156 to the cylinder 24 and outwardly therefrom through the conduit 150, the solenoid-actuated valve 146 and the conduit 152 into the fluid reservoir 128. Also, fluid entering the cylinder 22 from the conduit 148 passes through the conduit 158 into the cylinder 24, driving the piston 100 relatively toward the solenoid-actuated valve 146 and, thus, exerting a force through the piston rod 96 on the valve operating member 92 to aid in rotating the valve member 54.

As the piston 114 approaches the end of the travel as illustrated in FIG. 4, the switch actuating member 174 mounted thereon engages the switch 170 to move it to the closed position to energize the solenoid 149 on the valve 146. When the solenoid-actuated valve 146 is thus energized, the valve 146 is shifted by the solenoid 149 to the position wherein flow therethrough is in the direction of the solid arrows. Fluid flowing through the conduit 154 from the pump 124 is then diverted into the conduit 150 and into the cylinder 24.

As the fluid enters the cylinder 24, the piston 100 is driven relatively toward the pump valve 16. Also, the fluid flows through the conduit 156 into the cylinder 22 to drive the piston 98 relatively away from the pump valve 16. The combined forces exerted on the pistons 98 and 100 rotate the valve member 54 to a position (not shown) wherein the aperture 72 in the valve members 54 is in communication with the cylinder 14.

As the valve member 54 is shifted to the position described, the valve operating member 90 engages the switch 135. The engagement of the switch 135 and the valve operating member 90, closes the switch 135 and energizes the solenoid 119 on the valve 118. Energizing the solenoid 119 on the valve 118, shifts the valve 118 until the fluid flow path therethrough is in the direction of the solid line arrows illustrated in FIG. 4.

With the valve 118 in the position described, fluid from the pump 124 flows through the conduit 126 and the valve

118 into the conduit 120 and then into the hydraulic cylinder 110. As the fluid enters the hydraulic cylinder 110, the piston 108 is driven relatively toward the valve 16 and, by virtue of the connection between the piston rod 106, the piston 102, and the piston 108, drives the piston 102 in the cylinder 12 relatively toward the pump valve 16. As the piston 102 moves toward the pump valve 16, the slurry contained therein is driven through the adapter 38 into the annular space 66 in the pump valve 16 and outwardly through the opening 40 into the discharge member 42.

Simultaneously, slurry from the hopper 18 (see FIG. 3) flows downwardly through the discharge opening 19 into the interior of the valve member 54. From the interior of the valve member 54 the slurry flows through the apertures 72 into the adapter 38 filling the cylinder 14.

As the piston 108 moves relatively toward the pump valve 16, fluid passes through the conduit 142 into the hydraulic cylinder 116, moving the piston 114 relatively away from the pump valve 16. Movement of the piston 114 away from the pump valve 16, disengages the switch actuating member 174 carried by the piston rod 112 from the switch 170, thereby permitting the switch to open.

When the piston 102 reaches the end of its stroke, the switch operating member 163 closes the switch 162 and when the switch 162 closes, current flows to the solenoid 147 on the valve 146 so that the valve 146 is again moved to the position wherein the flow therethrough is in accordance with the dash arrows shown in FIG. 4.

With the solenoid-actuated valve 146 thus positioned, fluid from the pump 124 drives the piston 98 into the assumed initial position, that is, into the position illustrated in FIG. 4. As shown therein, the valve operating member 92 closes the switch 141, energizing the solenoid 121 on the valve 118, again shifting the valve 118 to the position wherein flow therethrough is in the direction of the dash arrows. When this occurs, the pump 10 has completed one complete cycle and it continues to operate in succeeding cycles as previously described.

It should be pointed out, that the discharge pressure exerted on the pump valve 16 by the movement of either the piston 102 or 104 relatively toward the pump valve 16 is exerted on the exterior of the valve member 54 in the annular space 66. With the pressure thus applied, it can be appreciated that the valve 16 is effectively prevented from freezing, that is, pressure locking in the valve housing 28 since the pressure tends to force the valve member 54 relatively away from the housing 28. Stated in another way, the pressure forces acting in the annular space 66 tend to force the valve member 54 and the valve housing 28 in relatively opposite directions and, thus, relatively away from each other to avoid the possibility of binding therebetween.

As previously mentioned, the hopper 18 (see FIG. 1) is attached to the valve 16 and, more specifically, the hopper 18 is attached to the upper annular flange 74 of the valve member 54. Thus, the hopper 18 moves with the valve member 54 as the valve member 54 is alternately positioned to provide communication between the aperture 72 and the cylinders 12 and 14. With the hopper 18 moving with the valve member 54, the relatively viscous slurry is constantly agitated and thus does not have an opportunity to adhere to the hopper 18, thus, preventing the discharge of the slurry from the hopper 18 into the valve member 54.

Embodiment of FIG. 5

FIG. 5 illustrates another embodiment of pump valve, generally designated by the reference character 200, and also constructed in accordance with the invention. It can be perceived in FIG. 5 that the valve 200 is basically similar to the valve 16 previously described.

The valve 200 includes a valve body 202 having a closed lower end 204 and a substantially open end 206. An annular member 208 is connected with the open end 206.

of the valve body 202 and extends inwardly terminating adjacent a valve member 210. An O-ring seal 212 is disposed in an O-ring groove 214 formed in the interior or bore of the valve body 202 relatively near the open end 206. A second O-ring seal 216 is disposed in an annular groove 218 formed in the interior of the valve body 202 relatively near the closed lower end 204. The valve body 202 includes spaced openings 205 and 207 extending through the wall thereof. A third opening, corresponding to the opening 40 (see FIG. 2) is also provided although it is not illustrated.

The valve member 210 includes an open end 220 and a closed lower end 222. The closed lower end 222 extends radially outwardly forming a flange 224 that has its periphery in sealing engagement with the O-ring seal 216. A flange 226 encircles the valve member 210 extending radially outwardly therefrom into sealing engagement with the O-ring seal 212.

A pair of vertically disposed members 228 and 230 (shown in dash lines in FIG. 5) extend between the flanges 224 and 226. It will be understood that the members 228 and 230 are constructed similarly to the members 68 and 70 previously described in connection with the valve 16. The members 228 and 230 have one edge (not shown) connected with the valve member 210 and the other edge thereon extending into sliding engagement with the interior of the valve body 202. An aperture 232 extends through the valve member 210 between the flanges 224 and 226 and between the members 228 and 230.

A shaft 234 extends from the closed lower end 222 of the valve member 210 through the closed lower end 204 of the valve body 202. A thrust bearing 236 encircles the shaft 234 and engages the closed lower end 204 of the valve body 202 to rotatably support the valve member 210 therein.

A second thrust bearing, designated by the reference character 238, encircles the valve member 210 above the flange 226. As clearly illustrated in FIG. 5, a lower race 240 of the thrust bearing 238 is connected with the valve member 210 while an upper race 242 engages the annular member 208 of the valve body 202. A sleeve 244 extends downwardly from the annular member 208 to slidably support the upper race 242. A plurality of threaded members 246 extend through the annular member 208 into engagement with the upper race 242. The threaded members 246 are provided so that the thrust bearing 238 can be forced downwardly relative to the valve body 202, thereby eliminating any vertical movement between the valve member 210 and the valve body 202.

A generally hemispherical hopper 18a having an opening 19a therein is connected with the open end 220 of the valve member 210. The hopper 18a is connected with the valve member 210 by a sleeve 250 that is attached to the hopper 18a and encircles the open end 220 of the valve member 210. A plurality of threaded fasteners 252 extend through the sleeve 250 into engagement with the valve member 210 to securely retain the hopper 18a thereon.

Valve operating members 254 and 256 are attached to the sleeve 250 and extend outwardly therefrom. As illustrated in FIG. 5, the piston rods 95 and 96 are pivotally connected with the valve operating members 254 and 256, respectively.

The valve 200 may be used in lieu of the valve 16 in combination with the pump 10. It should also be apparent from the foregoing detailed description that the operation of the valve 200, with the exception of the upper thrust bearing 238 which has been substituted for the sleeve bearing 84, is identical in operation to the valve 16.

The embodiments described in detail hereinbefore are presented by way of example only it should be understood that many changes and modifications can be made thereto without departing from the spirit of the invention or from the annexed claims.

What I claim is:

1. A pump valve comprising:
a housing having a bore extending partially therethrough defining an open end and a closed end and having first, second and third openings extending through the wall of said housing into said bore;
a valve member pivotally mounted in said bore and having a bore extending partially therethrough defining an open end and a closed end, the closed end of said valve member being disposed adjacent the closed end of said housing, said valve member having a first annular flange adjacent the open end of said valve member in sealing engagement with said housing,
a second annular flange adjacent the closed end of said valve member in sealing engagement with said housing,
a pair of spaced members connected with said valve member and extending between and connected with said flanges, and
an aperture extending through the wall of said valve member between said flanges and between said spaced members;
means journaling said valve member in said housing; and,
means connected with the open end of said valve member for pivoting said valve member from a position wherein said aperture is aligned with said first opening and said second and third openings are in communication to a position wherein said aperture is aligned with said second opening and said first and third openings are in communication.

2. A pump valve comprising:
a housing having a bore extending partially therethrough defining an open end and a closed end;
first, second and third openings extending radially through the wall of said housing into said bore;
first and second annular seals disposed in spaced annular grooves in said housing adjacent said bore, said first annular seal being located between said openings and the closed end of said housing, said second annular seal being located between said openings and the open end of said housing;
a hollow valve member having an open end adjacent the open end of said housing and journaled in said housing, the open end of said valve member being exposed through the open end of said housing for mounting an externally accessible material holding element thereon to move with said valve member relative to said housing and to feed material to the hollow interior of said valve member, said valve member being located in said bore and including a first annular flange sealingly engaging said second annular seal,
a second annular flange sealingly engaging said first annular seal member,
an aperture extending through the wall of said valve member into the interior thereof, said aperture being located between said annular flanges, and a pair of parallel spaced members extending between said flanges and disposed on each side of said aperture, said members being in engagement with said housing; and,
means connected with said valve member for pivoting said valve member from a position wherein said aperture is in communication with said first opening and said second and third openings are in communication to a position wherein said aperture is in communication with said second opening and said first and third openings are in communication.
3. A pump valve comprising:
a housing having a bore extending partially therethrough defining an open end and a closed end in said housing, said housing also having first, second and third radially spaced openings in the wall thereof

extending into said bore, a first annular groove adjacent said bore and between said openings and the open end of said housing, and a second annular groove adjacent said bore and between said openings and the closed end of said housing; 5 an annular seal disposed in each of said annular grooves; a valve member having a bore extending partially therethrough defining an open end and a closed end in said valve member, said open end being disposed adjacent the open end in said housing, said valve member also having an aperture extending through the wall thereof into the bore in said valve member; a first annular flange connected with the open end of said valve member and having a periphery proximate 15 said housing in said bore; first bearing means disposed between the periphery of said first annular flange and said housing to journal said valve member in said housing; a second annular flange connected with said valve member and having a periphery in sealing engagement with the annular seal in said first annular groove; 20 a third annular flange connected with said valve member in spaced parallel relation to said second annular flange and having a periphery in sealing engagement with the annular seal in said second annular groove, said second and third annular flanges being located on said valve member on opposed sides of said aperture; 25 a pair of parallel spaced members extending between and connected with said second and third flanges and with said valve member between said second and third flanges, said parallel spaced members being disposed on opposed sides of said aperture and each having an edge engaging said housing; second bearing means journaling the closed end of said valve member in the closed end of said housing; and, means connected with the open end of said valve member for pivoting said valve member from a position wherein said aperture is aligned with said first opening and said second and third openings are in communication to a position aligning said aperture with said second opening and said first and third openings are in communication. 30 4. The pump valve of claim 3 wherein said first bearing means includes: 45 a sleeve connected with the periphery of said first annular flange engaging said housing; and, means in said housing for lubricating the surface of said sleeve engaging said housing. 50 5. The pump valve of claim 4 wherein said second bearing means includes: 55 a shaft connected with the closed end of said valve member and extending through the closed end of said housing; and, a thrust bearing connected with the closed end of said housing and valve member and encircling said shaft for rotatably supporting said valve member in said housing against both thrust and radial forces. 60 6. A pump valve comprising: 65 a housing having a bore extending partially therethrough defining an open end and a closed end in said housing, said housing also having first, second and third radially spaced openings in the wall thereof extending into said bore, a first annular groove adjacent said bore and between said openings and the open end of said housing, and a second annular groove adjacent said bore and between said openings and the closed end of said housing; 70 an annular seal disposed in each of said annular grooves; a valve member having a bore extending partially therethrough defining an open end and a closed end in said valve member, said open end being disposed adjacent the open end in said housing, said valve mem- 75

ber also having an aperture extending through the wall thereof into the bore in said valve member; a first annular flange connected with the open end of said housing and having an inner periphery proximate said valve member; first bearing means disposed between said first annular flange and said valve member to journal the open end of said valve member in said housing; a second annular flange connected with said valve member and having a periphery in sealing engagement with the annular seal in said first annular groove; a third annular flange connected with said valve member in spaced parallel relation to said second annular flange and having a periphery in sealing engagement with the annular seal in said second annular groove, said second and third annular flanges being located on said valve member on opposed sides of said aperture; a pair of parallel spaced members extending between and connected with said second and third flanges and with said valve member between said second and third flanges, said parallel spaced members being disposed on opposed sides of said aperture and each having an edge engaging said housing; second bearing means journaling the closed end of said valve member in the closed end of said housing; and, means connected with the open end of said valve member for pivoting said valve member from a position wherein said aperture is aligned with said first opening and said second and third openings are in communication to a position aligning said aperture with said second opening and said first and third openings are in communication. 35 7. The pump valve of claim 6 and also including adjusting means operably connected with said first annular flange for adjusting the position of said first bearing means relative to said housing to eliminate relative vertical movement between said housing and valve member. 8. The pump valve of claim 7 wherein said adjusting means includes: an annular sleeve depending from said first annular flange and encircling said valve member; a thrust bearing having one race connected with said valve member and having the other race located for sliding movement in said annular sleeve; and a plurality of threaded members extending through and in threaded engagement with said first annular flange, said threaded members having one end engaging said other race, whereby rotating said threaded members moves said other race relative to said annular sleeve to eliminate relative vertical movement between said valve member and housing. 9. A pump for pumping concrete slurry comprising: first and second cylinders each having an open end and a closed end; a piston reciprocally disposed in each of said cylinders and having an elongated rod portion extending through the closed end of said cylinders; driving means connected with said rod portions for alternately reciprocating said pistons; a valve housing having a bore extending partially therethrough forming an open end and a closed end in said housing, said housing having a first opening in the wall thereof in communication with the open end of said first cylinder, a second opening in the wall thereof in communication with the open end of said second cylinder, and a third opening in the wall thereof; a valve member located in the bore in said housing and journaled therein and having a bore extending partially therethrough forming an open end and a closed end, the open end being disposed adjacent the open end of said housing.

a first annular flange sealingly engaging said housing between said openings and the open end of said housing,
 a second annular flange sealingly engaging said housing between said openings and the closed 5 end of said housing,
 a pair of parallel spaced members extending between said flanges, and
 an aperture extending through the wall of said valve member between said flanges and parallel 10 spaced members;
 a hopper member mounted on the open end of said valve member and having an opening therein in communication with the bore in said valve member; and, means connected with the open end of said valve member and operably interconnected with said driving means for pivoting said valve member from a position wherein said aperture is in communication with said first opening and said second and third openings are in communication when the piston in said second 20 cylinder is moving toward the open end of said second cylinder to a position wherein said aperture is in communication with said second opening and said first and third openings are in communication when the piston in said first cylinder moving toward the 25 open end of said first cylinder.

10. The pump of claim 9 wherein said driving means includes:

first and second hydraulic cylinders;
 a piston reciprocally mounted in each of said hydraulic 30 cylinders, each of said pistons being connected with a respective one of said rod portions;
 a hydraulic pump;
 means for driving said hydraulic pump operably connected therewith; and
 first shiftable valve means operably interconnected with said hydraulic pump and with said first and second hydraulic cylinders for directing fluid alternately to said hydraulic cylinders;
 first control means engageable with the means for pivoting 40 said valve member and connected with said valve means to shift said first valve means to alternate the flow of fluid to said hydraulic cylinders.

11. The pump of claim 9 wherein said means connected with the open end of said valve member for pivoting said valve member includes:

third and fourth hydraulic cylinders;
 a piston reciprocally disposed in each of said third and fourth cylinders and operably connected with said valve member;
 second shiftable valve means operably interconnected between said hydraulic pump and third and fourth hydraulic cylinders for directing fluid alternately to said third and fourth hydraulic cylinders; and,
 second control means engageable with one of said rod 55 portions and connected with said second shiftable valve means for shifting said second shiftable valve means to alternate the flow of fluid between said third and fourth hydraulic cylinders in timed relation with the movement of said rod portion.

12. The pump of claim 11 wherein said first and second shiftable valve means are solenoid-actuated, four-way valves; and, wherein said first and second control means include:

a source of electrical energy connected with each of said 65 solenoid-actuated, four-way valves; and,
 an electrical switch connected with said electrical energy and with a respective one of said solenoid-actuated, four-way valves.
 13. A pump valve comprising:
 a housing having a bore extending partially therethrough defining an open end and a closed end and having first, second and third openings extending through the wall of said housing into said bore;

a valve member pivotally mounted in said bore and having a bore extending partially therethrough and opening through one end of said valve member, the opposite end of said valve member being disposed adjacent the closed end of said housing, said valve member having
 a first flange extending at least partially around said valve member adjacent the open end of said valve member in sealing engagement with said housing,
 a second flange extending partially around said valve member and spaced therealong from said first flange and extending into sealing engagement with said housing,
 a pair of spaced members connected with said valve member and extending between and connected with said flanges, and
 an aperture extending through the wall of said valve member between said flanges, and between said spaced members;
 means journaling said valve member in said housing; and
 means connected with the end of said valve member carrying the opening of said bore therein for pivoting said valve member from a position wherein said aperture is aligned with said first opening, and said second and third openings are in communication, to a position wherein said aperture is aligned with said second opening, and said first and third openings are in communication.

14. A pump valve for dispensing a viscous material susceptible to setting up upon standing comprising:
 a hollow housing having an open end and having first, second and third openings extending through the wall of said housing and communicating with the hollow interior of the housing;
 a valve member pivotally mounted in said housing and having a bore extending partially therethrough and opening through an end of said valve member disposed at the open end of said housing, said valve member having
 a first annular flange secured around said valve member concentric to the pivotal axis of said valve member and in sealing engagement with said housing;
 a second annular flange secured around said valve member in spaced relation, and substantially parallel, to said first annular flange, and in sealing engagement with said housing;
 a pair of spaced members connected with said valve member and extending between, and connected with, said annular flanges; and
 an aperture extending through the wall of said valve member between said annular flanges and between said spaced members;
 a hopper secured to the end of said valve member through which said bore opens and having its interior communicating with the bore in said valve member; and
 means connected to said valve member adjacent said hopper for pivoting the hopper and simultaneously pivoting said valve member from a position wherein said aperture is aligned with said first opening in said housing, and said second and third openings are in communication, to a position wherein said aperture is aligned with said second opening, and said first and third openings are in communication.
